UNITED STATES PATENT OFFICE.

CHARLES WILLIAM LUMMIS, OF WATERBURY, CONNECTICUT.

APPARATUS FOR POURING MOLTEN MATERIALS.

1,089,139.

Specification of Letters Patent.

Patented Mar. 3, 1914.

Application filed January 9, 1912, Serial No. 670,258. Renewed July 5, 1913. Serial No. 777,495.

To all whom it may concern:

Be it known that I, CHARLES WILLIAM LUMMIS, a citizen of the United States, residing at Waterbury, in the county of New Haven and State of Connecticut, have invented a certain new and useful Improvement in Apparatus for Pouring Molten Materials, of which the following is a full, clear, and exact description.

10 The object of this invention is to provide for pouring molten materials from a container into a receiver at a definite or predetermined rate of pouring, so as to conform to the nature or condition of the material 15 and secure homogeneity and any other desired results or qualities in the product. For example, the invention as applied to molten brass admits of pouring the fluid from a crucible or other container directly 20 or indirectly into a mold or other receiver at a definite rate of pouring, so as to insure a product free from pipes, flaws, dirt and other defects which would impair its homogeneity, texture, ductility, malleability or 25 workable quality in rolling or other manipulation. To obtain the best results, it is necessary to have the molten material at practically a definite temperature, and to pour the material from the container at a definite 30 rate. The quantity of molten material poured during every interval of time throughout the pouring operation must be controllable, and whether the rate of pouring be uniform or variable, or a combination 35 of the two. The rate at which the molten material enters the receiver should be fast enough to keep the top of the material rising in the receiver in a fluid condition, so as to permit the dirt, dross or slag to separate and 40 float on the top; but it should not be so fast as to trap dirt and gases within the mass, or interfere with properly taking care of shrinkage as the poured mass cools or sets. The characteristics of this rate of pouring 45 vary in accordance with the temperature of the material being poured, its grade or composition, and the receptacle into which it is poured. Where these three conditions remain constant, or essentially so, a definite 50 rate of pouring is practicable to give the best results in producing a product free from defects, but where any or all of these conditions vary the rate of pouring should be such as to accommodate such variation. In the 55 past it has been customary to rely upon the

experience and skill of a furnace-man or caster to pour the material at the proper rate, and any mistake on his part resulted in imperfect or waste material; the imperfections oftentimes being internal in the product and only discovered when the product was worked up. The present invention substitutes an automaton for a human being, so that by mechanical means the pouring rate may be automatically controlled to obtain 60 the requisite speed, whether uniform or variable, and insure a product free from essential defects.

While the invention originated in the making of brass, it is to be understood that 70 it is applicable to other alloys, metals and plastics which are transformed by heat into a fluid condition and in this condition reduced to useful or workable shapes in molds or otherwise. From this it will appear also 75 that the container from which the molten material is to be poured may be a crucible, ladle, melting pot, furnace, or other apparatus, and the material may be poured 80 thence into the mold or other receiver, or indirectly through a strainer or other intermediate vessel or delivery device.

I will proceed now to describe the invention in connection with the manufacture of brass, retaining however the reservation just 85 above noted as to the extension of the invention to other materials or substances, and observing that the apparatus shown and described as embodying the invention is typical, and hence susceptible of wide variation without departure from the principle 90 of the invention.

In the accompanying drawings illustrating the invention, in the several figures of which like parts are similarly designated, 95 Figure 1 is a top plan view of a bodily tiltable crucible furnace, showing one embodiment of the invention. Fig. 2 is a vertical section illustrating one form of crucible furnace available for the purposes of 100 this invention. Fig. 3 is a side elevation omitting the mechanism for turning the tilting-restraining device and showing the parts at rest in melting position, and Fig. 4 is a similar view showing the furnace in 105 pouring position. Fig. 5 is a side elevation showing the parts of Figs. 3 and 4 in position for lowering the furnace into melting position after pouring. Fig. 6 is an elevation of a cam illustrating one form of 110

restraining device. Fig. 7 is a side elevation showing an air hoist for tilting the furnace. Fig. 8 is a side view showing an arrangement for positively tilting a container and also restraining or controlling its tilting movement.

The furnace 1 may be of any suitable construction, and is here shown as of the crucible variety, and adapted to receive a crucible 2 containing the charge to be melted. The furnace may be mounted on trunnions arranged at its sides, but as shown in Figs. 1, 3, 4 and 5, the trunnions 3 may be located substantially on a line with the pouring mouth or other discharging member or element, and mounted in stands 4, which are erected on a suitable support. At least one of these trunnions is fixed to turn with the furnace, and it is extended laterally and provided with an arm 5 on which is a roller 6. By arranging the trunnions as shown at or near the pouring mouth, the receiver or mold may be of comparatively small dimensions and may remain stationary while being filled; whereas if the furnace is pivoted at the sides as usual, the receiver must be large or else moved to conform to the motion of the pouring spout. A shaft 7 suitably mounted is arranged to receive and rotate a cam 8, adapted for co-operation with the roller 6 on the arm 5. The shaft 7 may be turned by any suitable mechanism, such for example as a toothed wheel 9 meshing directly or indirectly with the pinion 10 on any suitable motor 11; it being understood that the shaft 7 is turned at a definite speed, by any suitable power mechanism.

The furnace 1 may have any suitable cover, such as a counterweighted cover 12, over the opening in which is a counterweighted auxiliary cover 13, in accordance with approved practice. The furnace covers herein shown may be made removable for pouring purposes, or I may use other covers of any suitable design adapted to be placed in position over the furnace and crucible during the melting of the charge and capable of being replaced by covers suitable for pouring purposes when the pouring operation is being carried on.

The bottom of the furnace is provided with an arm 14 extending outwardly from the rear, and this arm has connected to it a rope or other lifting agent 15 passed over pulleys 16 to a counterweight 17. This sort of hoist may be operated in any usual way. But, as shown in Fig. 7, the hoist may be replaced by an air-cylinder 18, or other suitable power mechanism, of any usual or approved construction and capable of tilting the furnace on its trunnions for pouring purposes and restoring it again to horizontal position for melting purposes, the cam 19 being used as the restraining medium, as previously

described. Furthermore, as shown in Fig. 8, the arm 14 may be connected by a rope or chain or other medium 19 to a lever 20 fulcrumed at 21 and having a laterally extending roller 22 engaged by a rotary cam 23. This cam 23 is in all essential respects the same as cam 8 previously described and may be operated by similar means. Obviously in this arrangement the cam not only restrains the tilting of the furnace as in the arrangement previously described, but in addition it also positively tilts the furnace. The arrangement shown in Fig. 8 also illustrates the use of a furnace pivotally mounted at its sides instead of at or near its pouring edge. During the melting operation, the cam 8 is in such engagement with the roller 6 that the furnace may be held stationary, but when power is applied to the shaft 7 at the time when the charge is ready for pouring, the cam is turned upwardly so as to release the roller sufficiently to allow the counterweight 17 to act to tilt the furnace upon its trunnions 3, but the rate of tilting is controlled by the cam, and the cam is given a configuration that will regulate the pouring in accordance with the predetermined rate at which the molten material is to be or should be poured in order to get the best results. Or in other words, the pouring motion of the container is so regulated that the container is tilted, in each interval of time, through the angle which is necessary in order to pour out the desired quantity of molten material in each interval in accordance with the predetermined plan.

In practical operation, when the grade of material to be poured and the receptacle into which it is poured are kept the same, the temperature of the molten material is brought to a definite point which can be determined by pyrometers or other means of measuring temperatures, and the cam designed to suit these conditions is used to regulate the pouring. When the grade of material, the receptacle, or both are changed, the temperature of the molten material is brought to a point best suited to meet these particular conditions, and a cam designed to regulate the pouring so as to produce the best results with the changed conditions is substituted. This cam is used as long as the other conditions remain constant. After the pouring is completed, the furnace may be returned to melting position by hoisting the counterweight 17 by any suitable tackle 24, for example, as shown in Figs. 3 and 4, and appropriately returning the cam, the cam remaining stationary in its final pouring position until after the furnace has been returned to melting position, said cam being then turned into position to bear upon the roller on the arm 14 on the trunnion. The air or power hoist 18

of course is used both to tilt and return, and this is true likewise of the arrangement shown in Fig. 8.

The cam or restraining device is shown in Figs. 1, 3, 4, 5 and 7 as fixed directly to its operating shaft, but if desired it may be mounted upon a holding device 25, as indicated by dotted lines in Fig. 7, and said holding device may be in the form of a 10 circular plate to which the cam is suitably secured.

Referring to Fig. 6, which illustrates a cam of a contour that will give the desired pouring action in casting brass, that face of 15 the cam from the points 26 to 28 or thereabout will hold, in connection with the roller arm, the furnace stationary, and from 28 to 29 will start the active pouring, and from 29 to 30 will control the pouring action 20 to completion, in conformity with best hand practice, but with the advantage that the pouring action is not exposed to undue and undesirable variations such as befall a human agent by diversion of his attention, 25 unsteadiness, misstep or other accident.

The furnace may be heated in any suitable way, and I have shown in Fig. 1, at 31, an oil burner of the atomizer type as the medium for supplying the necessary 30 melting heat.

As already sufficiently indicated, the pouring may be directly into molds or other receivers, or the material may be poured in the first instance into an intermediate vessel and flow thence into the molds.

The invention may be carried out with a ladle or other container removable from the melting furnace itself, and in such case the container would be mounted in a holder 40 equipped with the pouring-controlling mechanism.

It is to be understood that the principle of the invention herein explained is susceptible of many other variations than those set 45 forth; and it is to be noted that the invention differs fundamentally, in the use and function of its cam or restraining device, from those prior inventions in which the metal has been poured from the vessel in which it 50 is melted without removing the vessel from the furnace, by bodily tilting the furnace containing the vessel by mechanical means under human operation. In my invention 55 human agency with its limitations is eliminated during the pouring operation.

The gist of the invention, irrespective of the means employed, lies in the substitution for the human element in pouring of an automatic mechanical element, with the resulting uniformity of operation.

What I claim is:—

1. An apparatus for pouring molten materials, comprising a container for the molten material, means to support said container so that it may be tilted, and means

to impart a definite rate of tilting movement to said container so that the quantity of molten material poured from said container in each interval of time during the pouring operation is automatically controlled in accordance with a predetermined plan. 70

2. An apparatus for pouring molten materials, having a container for the molten material, means to support said container so 75 that it may be tilted, and means to tilt said container including a member operating to automatically control the angle of movement of the container during each interval of time throughout the pouring operation and thereby control the quantity of material so poured in accordance with any predetermined plan. 80

3. An apparatus for pouring molten materials, having a container for the molten material, means to support said container 85 so that it may be tilted, and means to tilt said container including a member operating to automatically control the angle of movement of the container during each interval of time throughout the pouring operation and thereby control the quantity of material so poured in accordance with any predetermined plan, said controlling member capable of change to produce the desired 90 predetermined rate of pouring. 95

4. An apparatus for pouring molten materials, comprising a container for the molten material, means to support said container so that it may be tilted, and means to tilt said container through a predetermined angle in each interval of the time in which the tilting takes place and thereby pour out the contents at a predetermined variable rate. 100

5. An apparatus for pouring molten materials, comprising a container for the molten material, means to support said container so that it may be tilted, means tending to tilt said container, and a restraining member to automatically limit the angle 110 through which the container is tilted during each interval of the time in which the tilting movement takes place, and thereby cause the contents to be poured from the container at a predetermined rate. 115

6. An apparatus for pouring molten materials, the combination of a container for the molten material, means to tilt said container, a cam and means interposed between the cam and the container to regulate the 120 tilting movement of the container, said cam having its active contour developed to secure a predetermined rate of pouring of the contents of the container throughout the operation of pouring. 125

7. In apparatus for pouring molten materials, the combination of a container, a fixed support for said container, means to tilt the container in its support, an arm connected with the container, and an independ- 130

- ent cam coöperating with said arm to automatically vary the tilting movement and secure a predetermined definite rate of pouring throughout the pouring operation.
5. 8. In apparatus for pouring molten materials, the combination of a tilting container for the molten material, a cam having an active contour described on lines to secure a predetermined rate of pouring action, and 10 means connected with the container and interposed between it and the cam and coöperating with both to effect a predetermined rate of pouring action and thereby control the quantity of molten material poured during 15 every interval of time throughout the pouring operation, so as to insure the desired homogeneity of product.
9. An apparatus for pouring molten materials, comprising a tilting container for 20 the molten material, an arm connected with the container, and a cam coöperating with said arm to regulate the tilting movement in accordance with a predetermined variable rate of pouring so as to control the quantity 25 of molten material poured during every interval of time throughout the pouring operation.
10. An apparatus for pouring molten materials, comprising a tilting furnace having 30 trunnions, a roller arm fixed to one of the trunnions so as to turn with the furnace, and a rotary cam mounted in coöperative juxtaposition to the roller arm and of a contour to insure a predetermined rate of pouring.
- 35 11. An apparatus for pouring molten materials, comprising a container for the molten material, means for tilting the container to pour out its contents, and a restraining medium including a member turning upon a 40 fulcrum in fixed relation to the container and a rotary cam arranged in coöperative relation to said fulcrumed member and of a contour to give a definite predetermined rate of pouring as the container is tilted.
- 45 12. An apparatus for pouring molten materials, comprising a container for the molten material provided with trunnions arranged adjacent to its point of discharge, a support in which said trunnions are mounted to permit the container to be tilted, a roller arm turning with the container as it is tilted, and a rotary cam coöperating with the roller arm to control the tilting movement of the container in accordance with a predetermined rate of pouring, so that in the case of casting molten metals the pouring may be regulated to insure the proper filling of the molds.
- 50 13. In an apparatus for pouring molten materials, a container for the molten material, means to support said container so it may be tilted, a piston equipped compressed air cylinder operatively connected with said container to impart a tilting motion thereto, and means for controlling the angle of movement of said container during each interval of time throughout the pouring operation.
- 55 In testimony whereof I have hereunto set 70 my hand this eighth day of January A. D. 1912.
